CLAIM

The ornamental design for a faucet base, as shown and described.

DESCRIPTION

FIG. 1 is a front perspective view of a first embodiment of the faucet base;

FIG. 2 is a front elevational view of the first embodiment of the faucet base;

FIG. 3 is a rear elevational view of the first embodiment of the faucet base;

FIG. 4 is a left side elevational view of the first embodiment of the faucet base;

FIG. 5 is a right side elevational view of the first embodiment of the faucet base;

FIG. 6 is a top elevational view of the first embodiment of the faucet base;

FIG. 7 is a bottom elevational view of the first embodiment of the faucet base;

FIG. 8 is a front perspective view of a second embodiment of the faucet base;

FIG. 9 is a front elevational view of the second embodiment of the faucet base;

FIG. 10 is a rear elevational view of the second embodiment of the faucet base;

FIG. 11 is a left side elevational view of the second embodiment of the faucet base;

FIG. 12 is a right side elevational view of the second embodiment of the faucet base;

FIG. 13 is a top elevational view of the second embodiment of the faucet base; and,

FIG. 14 is a bottom elevational view of the second embodiment of the faucet base.

The features shown in broken lines in FIGS. 1-14 illustrate environmental features that form no part of the claimed design.

1 Claim, 12 Drawing Sheets
